UNITED STATES PATENT OFFICE.

JOHN L. FLANNERY, JR., OF CHICAGO, ILLINOIS, ASSIGNOR TO THE BOYE NEEDLE COMPANY, OF CHICAGO, ILLINOIS, A CORPORATION OF ILLINOIS.

DESIGN FOR A NEEDLE-WRAPPER.

54,732.

Specification for Design. Patented Mar. 23, 1920.

Application filed June 21, 1919. Serial No. 305,904. Term of patent 14 years.

To all whom it may concern:

Be it known that I, JOHN L. FLANNERY, Jr., a citizen of the United States, residing at Chicago, county of Cook, and State of Illinois, have invented a new, original, and ornamental Design for a Needle-Wrapper, of which the following is a specification, reference being had to the accompanying draw-

ing, forming a part hereof, in which the drawing represents a plan view of a needle-wrapper embodying the design before the wrapper is folded.

I claim:

The ornamental design for a needle-wrapper, as shown.
